CUTTING MACHINE FOR PAPER, CARD-
BOARD AND THE LIKE PROVIDED WITH
AUTOMATIC MEANS FOR FEEDING THE
MATERIAL TO BE CUTGerhard Schmidt, Leipzig, Germany, assignor to
Karl Biagosch, Leipzig, Germany

Application March 23, 1931, Serial No. 524,614

3 Claims. (Cl. 271—54)

The present invention relates to cutting or severing machines for paper, cardboard and the like provided with a device for automatically feeding the material to be cut. In cutting machines for paper, cardboard and the like, devices for the automatic feed of the material are known in which an intermittent feed is effected by means of a friction coupling adapted to be engaged and disengaged, and wherein the engaging or disengaging operation takes place before the commencement or after the termination of the feeding movement in such manner that the said engaging or disengaging operation is independent of the feeding movement. In order to maintain the coupling in the engaged position the forked lever operating the said coupling is held in its end position corresponding to the engaged position of the said coupling by means of a stop member or lever which comes into position in front of the said forked lever as soon as this latter has arrived in the end position corresponding to the engagement of the coupling, and thereby prevents the lever from executing a return movement. In order, however, that the stop member should be able to come into position without hindrance in front of the forked lever of the coupling it is necessary to impart to the said forked lever a certain amount of extra movement so that in this manner space providing play is obtained between the stop member and the forked lever, over which space the said forked lever then moves back again so as to rest closely up against the stop member. This small backward movement of the forked lever for the coupling necessitates however a backward movement of the friction coupling of corresponding magnitude, whereby the said coupling is also allowed a certain amount of play. In order to obtain reliable and exact feeding of the material to be cut it is, however, necessary to maintain the movable part of the coupling positively in its end position corresponding to the engagement of the coupling, in order to avoid any slipping action on the coupling. It is the principal object of the invention to attain this end. With this object in view according to the invention a resilient or spring-controlled intermediate member is inserted in the linkage controlling the coupling in such manner that the extra movement of the forked coupling lever necessary for the engagement of the stop arm is taken up by the said resilient intermediate member. As a result of this the movable part of the coupling does not participate in the small backward movement of the forked lever into its position of rest against the stop lever. The said

movement is compensated for by the action of the resilient intermediate member so that the coupling remains in a reliable condition of engagement.

A preferred constructional form according to the invention is illustrated by way of example on the accompanying drawings, in which:

Fig. 1 is a plan and

Fig. 2 is an elevation drawn to a larger scale and partly broken off, of a cutting machine 10 equipped with the device according to the invention.

In both figures of the drawings the details of construction which are not essential for the comprehension of the invention are omitted.

Referring to the drawings the reference numerals 34 and 35 denote two frame supports between which a horizontal operating table 36 and a knife-beam 37 provided with a knife 37a and arranged so as to be movable in a vertical direction are arranged in known manner.

A crank pin 1 provided on a crank disk 2 which is rigidly mounted on a crank shaft 3 journalled in the frame support 34 transmits by means of a connecting rod 4 and a swinging arm 5, a reciprocating motion to a shaft 6 journalled in the other frame support 35. This swinging movement is transmitted by means of bevel wheels 7 and 8 to a vertically journalled shaft 9 and from this latter to a swinging arm 12. A toothed rack 13 is pivotally connected by means of a pivot pin 14 arranged so as to be adjustable (the adjustment not being shown on the drawings) to the swinging arm 12 and engages with a pinion 15 which is rigidly mounted on a shaft 16 journalled between the supports 34, 35 below the table 36 in the frame of the machine. As a consequence of the to-and-fro motion of the swinging arm 12 the pinion 15 and consequently also the shaft 16 have a rotary motion of greater or less magnitude imparted to them according to the adjustment of the pivot pin 14 of the rack 13.

On the shaft 16 a pinion 19 engaging with a toothed crown wheel 17 provided on a belt pulley 11a and adapted to be coupled by means of a friction coupling 18 with the shaft 16 is loosely mounted. When the pinion 19 is connected with the shaft 16 by means of the coupling 18 the belt pulley 11a participates in the rotary motion of the pinion 15 and thereby actuates by means of an endless steel band 20 a saddle member 21 by means of which the material to be cut is pushed forward on the operating table 36 in the direction towards the knife 37a.

The engagement of the coupling 18 is effected

by means of a forked coupling lever 22 which is mounted so as to be capable of swinging by means of a pivot pin 22a. The forked coupling lever 22 is provided with an extension 23 against which 5 one arm of a bell crank lever 24 adapted to swing about the pivot pin 22a presses through the medium of an intermediate compression spring 25. The movement of the bell crank lever 24 is caused on the one hand by means of a pull rod 26 which 10 pivotally connects the said bell crank lever 24 with a bell crank lever 27 pivoted at 27a, and a cam disc 28 mounted on the crank shaft 3 and provided with cams 28a which operate on an anti-friction roller 27b of the said bell crank 15 lever 27, and on the other hand by means of a tension spring 32 acting on the pull rod 26.

The mode of operation of the automatic feeding device according to the invention is as follows:

When the crank pin 1 passes through one of 20 its dead centres, the whole feeding mechanism and consequently also the pinion 15 remain for a short time at rest. During this period of rest the coupling 18 is brought into the position of engagement by means of the forked coupling 25 lever 22 through the medium of cam 28a provided on the cam disc 28, the bell crank lever 27, the pull rod 26, the bell crank lever 24 and the compression spring 25. The bell crank lever 24 acts as a locking member and is maintained in its 30 end position corresponding to the position of engagement of the coupling by means of a stop member 29, the locking projection of which comes into position in front of the one arm of the bell crank lever 24. A spring 29a which is arranged 35 between the stop member and an extension 29b provided on a bearing bracket 29c of the stop member, presses the said stop member into the locking position. Inasmuch as the movement of the bell crank lever 24 is transmitted by means 40 of the compression spring 25 to the forked lever 22, the spring 25 becomes compressed when extra movement of the bell crank lever 24 with regard to the coupling movement of the coupling 18 takes place, to a corresponding extent and therefore 45 maintains the coupling in the completely engaged position in spite of the return movement of the bell crank lever 24 until stopped by the locking projection of the stop member. As a result of the half revolution of the crank pin 1 50 up to its next dead centre the saddle member 21 is pushed forward by the feeding mechanism to an extent corresponding to the adjustment of the pivot pin 14 of the rack 13 on the swinging arm 12. When the crank pin 1 has arrived in 55 its second dead centre position and the whole feeding mechanism thus again becomes stationary for a short period, the bell crank lever 27 and consequently also the pull rod 26 are moved back through the action of the second cam provided on the cam disc 28. As the pull rod 26 is 60 connected with the lever 24 through the medium of a slot the said lever 24 does not at first participate in the return movement of the said pull rod. During this part of the return movement of the pull rod 26 a cam 30 provided on the pull rod presses the stop member 29 back, whereby 65 the lever 24 is released and is likewise enabled to execute a return movement. This movement is transmitted by means of the screw bolt 31 to the forked coupling lever 22 and thus also to the coupling 18 which is thereby disengaged. The coupling members are maintained in the position of disengagement by the tension spring 32 operating on the rod 26. During the succeeding 70 75 second half rotation of the crank pin 1 the belt

pulley 17 does not participate in the backward movement of the feeding mechanism in consequence of the disengagement of the coupling, and the saddle member 21 thus remains stationary. During this period the cutting movement of the knife 37a takes place.

The backward movement of the saddle member 21 is effected by turning the belt pulley 17 backwards by hand or by mechanical means during the time when the machine is at rest. The 10 resilient intermediate member, i. e. the spring 25, which in the constructional form described by way of example is arranged between the forked coupling lever 22 and the bell crank lever 24 may also be arranged in another position, for example 15 in the pull rod 26 or the bell crank lever 27. The only condition is that the said resilient intermediate member is located between the coupling and that part of the device for engagement, the motion of which is stopped by the stop member 29. 20

I claim:

1. In a cutting machine for paper, cardboard and the like, provided with an automatically operating device for intermittently feeding the material to be cut, comprising a coupling adapted to be engaged and disengaged during the intermittent periods of rest of the operating device, the combination of: co-operating movable and stationary friction coupling members; means acting upon said friction coupling members to bring them in and out of engagement with one another; a locking device adapted to secure said means in the position corresponding to engagement of said friction coupling members; a resilient member interposed between the movable friction coupling member and that member of said means which is engaged by the locking device; and means for automatically releasing said first-named means.

2. In a cutting machine for paper, cardboard and the like, provided with an automatically operating device for intermittently feeding the material to be cut, comprising a coupling adapted to be engaged and disengaged during the intermittent periods of rest of the operating device, the combination of: co-operating movable and stationary friction coupling members; means acting upon said friction coupling members to bring them in and out of engagement with one another said means comprising two levers loosely mounted relatively to one another; a compression spring interposed between said levers; and a locking member adapted to hold one of said levers positively in the position corresponding to engagement of said friction coupling members.

3. In a cutting machine for paper, cardboard and the like, provided with a device for automatically feeding the material to be cut by means of an intermittently operated feeding member comprising a coupling adapted to be engaged and disengaged during the intermittent periods of rest, the combination of: a friction coupling device; a forked lever operatively associated with said friction coupling device; a spring-controlled bell crank lever operatively associated with said forked lever by means of the spring control which is interposed between the two levers; a stop member pivoted to the framework of the machine and limiting the movement of said bell crank lever; and a spring controlled rod operatively connected with said bell crank lever and the drive of the machine, substantially as described.
